UNITED STATES PATENT OFFICE.

WILLIAM HECKMAN AND JOHN A. HECKMAN, OF DENVER, COLORADO, ASSIGNEES TO
THE HECKMAN SIGNAL COMPANY, A CORPORATION OF COLORADO.

DESIGN FOR AN AUTOMOBILE SIGNAL.

Application filed May 16, 1921. Serial No. 470,012. Term of patent 14 years.

To all whom it may concern:

Be it known that we, WILLIAM HECKMAN and JOHN A. HECKMAN, citizens of the United States, residing at Denver, in the county of Denver and State of Colorado, have invented a new, original, and ornamental Design for Automobile Signals, of which the following is a specification, reference being had to the accompanying drawing, forming part thereof.

Figure 1 is a view in front elevation of an automobile signal showing our new design;

Fig. 2 is a view in side elevation of an automobile signal showing our new design.

We claim:

The ornamental design for an automobile signal as shown.

WILLIAM HECKMAN.
JOHN A. HECKMAN.
